PETER MCINTYRE, OF NORWICH, CONNECTICUT.

Letters Patent No. 97,668, dated December 7, 1869.

IMPROVEMENT IN DRAIN-PIPE MACHINES.

The Schedule referred to in these Letters Patent and making part of the same

To all whom it may concern:

Be it known that I, PETER MCINTYRE, of the city of Norwich, county of New London, and State of Connecticut, have invented a new and useful Machine for Making Drain-Pipe of Hydraulic Cement or other suitable substance while in a plastic condition; and I do hereby declare that the following is a full, clear, and exact description of the construction and operation of said invention, reference being had to the accompanying drawings, and to the figures and letters marked thereon, and in which—

Figure 1 is a front elevation.

Figure 2, a side elevation.

Figure 3, a vertical section through the axis of the pipe-mould.

Figure 4, a top view of the gearing.

Figure 5, a top view of the pipe-mould.

Figure 6, section through axis of driving-shaft, showing how the gears are engaged and disengaged.

Figure 7, a side elevation of the wallower and pipe-core rack.

The same parts are indicated by the same letters in all the figures.

The nature of my invention consists in such combination and arrangement of suitable moulds and machinery as will produce drain-pipes, of hydraulic cement or suitable material of analogous character, while in a plastic condition.

Heretofore, drain-pipes have been exclusively made by manual labor, the material being rammed down into the annular space between the outer mould and the central core of the pipe, which is a tedious and laborious operation, and for the most part defective in result.

To enable others skilled in the art to make and use my invention, I will proceed to describe its construction and operation.

I make the outer mould A A of the pipe of metal, with a smooth central cavity, of the necessary length, size, and shape, for the exterior of the proposed pipe.

This mould is divided longitudinally into two equal parts, as shown, which are readily secured to each other by the hooks and pins a a, and also by the cap-piece B, for finishing the end of the pipe, which is made to embrace both the sides of the mould A A, and is secured to them by the catches and pins c c, which is effected by a partial rotation of the cap-piece B upon the mould A A.

The mould A A is also secured to the bed-piece C, which is attached to the top floor or frame of the machine by means of the holders d d and guide-pins e e.

The interior of the pipe is made by the action of the plungers D and E. The plunger E is a hollow cylinder, and through it the plunger D is made to pass. Both these plungers move upward at the same

time, but the plunger E, which forms the bell-mouth of the pipe, having a short motion, is quickly elevated to the proper height by means of a cam formed upon the side disks of the wallower, as will presently be more fully explained. The plunger D is a solid cylinder, corresponding in size to the bore of the pipe, and having its upper end conical, as shown, the whole of which conical part passes out through the cap-piece B, which has a central opening in it of proper size for that purpose.

I prefer to form the bell-mouth of the pipe by the action of the plunger E, but the part E may be stationary within the mould, and attached to the bed-piece C, or be so attached to it as to permit of a short rotative vibration, when required, to break the adhesion between it and the newly-formed pipe, in which case the bell-mouth of the pipe must be made first by pressing the material into that part of the mould.

The plunger D is attached to the upper end of the rack F, the teeth of which gear or take into the trundles or rounds of the wallower G, and is made to work up and down to the necessary extent by the forward and reverse movements of the wallower; and the hollow plunger E, for making the bell-mouth of the pipe, is attached to and is worked by the lever H, which is composed of two flat bars, pivoted to the framing of the machine, at m, and connecting with the plunger E below the bed-piece C, by means of the two studs h h, on its opposite sides, the points of which studs enter into short horizontal grooves in the lower part of the plunger, as shown in fig. 3, so as to admit of a rotative movement or vibration on its axis, to break the adhesion between the newly-formed pipe and the bell-mouth plunger, which is accomplished by the hand-lever I, fig. 4.

The front end of the lever H is formed into a pair of arms, which rest upon and take into the grooved or slotted part of the cams made in the heads of the wallower G, to raise and retract the bell-mouth plunger E, as shown in fig. 6.

The machine is operated by the crank J, on the outer end of the shaft K, either by hand or by any other convenient first mover.

Upon this shaft there is a fixed pinion, L, and a loose wheel, M; also the loose wallower G, and the fast clutch-plate, O.

Parallel with this shaft there is a second shaft, N, having a wheel, P, at one end, into which the pinion L gears, and at its opposite end the pinion Q, which gears into the loose wheel M on shaft K. Both these shafts are mounted in proper bearings, as shown in fig. 4.

Upon the shaft K is also the slider R, carrying the bayonets n n, which pass through the wallower G, and serve as carriers for it, and combine it with the

clutch-plate O or the loose wheel M, as they are moved toward and made to engage with one or the other, by means of the lever S, fig. 4.

When the bayonets *n n* enter the holes in the clutch-plate O, which is fast upon the shaft K, the wallower will have the same speed as the crank J, and will therefore have a quick motion, which motion I use for drawing down the plunger D, on completing the pipe; and by moving the lever S in the opposite direction, so as to withdraw the bayonets *n n* from the clutch-plate O, and insert them in the holes made for their reception in the loose wheel M, the wheel M will thereby become locked to or combined with the wallower G, and will consequently give it the increased power and reduced speed of the wheel M, according to the relative proportions of the wheels and pinions used in the train.

Having thus described the construction and operation of the mechanism, I shall now describe the process of making a drain-pipe therein.

The plungers D and E being at the lowest position in the mould A A, I pour or drop into the mould a sufficient quantity of the cement or material for the required pipe, which must be at the time in a soft or plastic condition. I then turn the crank J with the increased power of the gearing on the wallower G, forcing the hollow plunger E up into the bell-mouth of the pipe, and the plunger D gradually up to the necessary height in the mould, the surplus material, if any, being forced out at the top of the mould by the conical part of the plunger D, as it passes out through the cross-piece B, which completes the pipe. I now reverse the lever S, so as to disengage the wallower G from the wheel M, and engage it with the clutch O, attached to the shaft K; then, on reversing the motion of the shaft K by the crank J, and also making a few lateral vibrations of the lever I, fig. 3, so as to give a small alternate rotative movement to the hollow plunger E of the bell-mouth, and thereby break the adhesion between it and the newly-formed pipe, the plunger D is first rapidly withdrawn from the mould, or the interior of the newly-formed pipe, during which operation the hollow plunger supports the pipe in the mould, and then the hollow plunger E is withdrawn. The rapid descent of the plunger serves to polish or smooth the inside of the pipe.

To take the pipe from the mould, the cap B is first moved around sufficiently to disengage the catches *c* from the holding-pins; the side parts A A are then opened and taken off the bed-plate; and lastly, the finished drain-pipe is removed from the machine, and deposited in a convenient place to harden.

After removing the pipe, the several parts of the mould may be immediately put together and in place upon the machine, and the operation repeated.

The pipes, by this arrangement and mode of oper-

ation, are produced with great rapidity, when compared with hand-labor, and of much better quality.

The machine should be made to receive different sets of moulds and plungers, to suit the various sizes of drain-pipe that are required; but if they are to be very small or very large, it would be advantageous to have the machines of corresponding proportions.

I have herein described an operative machine that has been proved to work well in practice, but as the means described are not the only ones by which the various motions may be produced, I do not confine myself to the exact arrangement of the gearing herein given; for instance, a screw may be substituted for the rack F, and a screw-wheel or a spur-wheel, with a nut in its centre to work on such vertical screw, be substituted for the wallower or spur-wheel G, and one speed only may be used, instead of the fast and slow speeds I have mentioned, and still the operation and result be substantially the same as by the means I have shown and described. I do not, therefore, limit myself to any particular system of gearing, but claim the right, under this patent, to adopt and use any system of gearing that will best suit the intended purpose.

Having thus described the construction and mode of operating my drain-pipe-moulding machine,

What I claim therein as my own invention, and desire to secure by Letters Patent, is—

1. The combination of the outer mould with the solid and hollow plungers, for forming and completing the pipe and its bell-mouth at one operation, in the manner and by the means substantially as described.

2. The axial movement of the plunger of the bell-mouth, to break the adhesion between the said plunger and the newly-formed pipe, in the manner and for the purpose substantially as described.

3. The combination of the solid and hollow plungers with the operating-gearing, in such wise as to elevate the hollow plunger to the proper height for the bell-mouth, before the solid plunger has advanced any or much within the pipe-mould, and retaining it in that position till the solid plunger has completed its full stroke, and is withdrawn from the mould, or nearly so, before dropping the hollow plunger, in the manner and for the purposes substantially as described.

4. The combination of the cap-piece B, pins C, and hooks V, with the side parts A A, when constructed and arranged to operate as shown and described, for the double purpose of clamping said parts A A together, and closing and completing the top of the mould around the plunger, in the manner substantially as set forth.

PETER McINTYRE.
